S. W. RUGGLES,

Burglar Alarm.

No. 15,440.

Patented July 29, 1856.

Fig: 1.

Fig. 2

UNITED STATES PATENT OFFICE.

S. W. RUGGLES, OF FITCHBURG, MASSACHUSETTS.

PICKPOCKET-DETECTOR.

Specification of Letters Patent No. 15,440, dated July 29, 1856.

To all whom it may concern:

Be it known that I, S. W. RUGGLES, of Fitchburg, in the county of Worcester and State of Massachusetts, have invented a certain new and useful Improvement on Alarm-
5 Detectors, which I term a "Pickpocket-Detector;" and I do hereby declare that the following is a full, clear, and exact description of the same, reference being had to the 10 annexed drawings, making a part of this specification, in which—

Figure 1, is an internal view of my improvement, the case being bisected, as indicated by the line (x) (x) Fig. 2. Fig. 2, 15 is a transverse section of the case and bell, the plane of section being through the center.

Similar letters of reference indicate corresponding parts in the two figures.
20 My invention has reference to that description of pocket or portable alarm detectors in which a spring wheel or barrel, having teeth or projections on it or connected with it, is employed to operate the 25 hammer of a bell and in which the alarm is started and actuated by pull on a string or chain attached to the detector.

To enable those skilled in the art to fully understand and construct my invention, I 30 will proceed to describe it.

A, represents a case, which may be constructed similar to a watch case, and about the same size. Within the case A, there is placed upon an axis (a) a wheel B, having 35 teeth or projections (b) on one side, and a coil spring (c) is attached to the wheel B, and axis (a), the axis being stationary and the wheel B, turning upon it.

C, represents a hammer, which is attached 40 to a tongue or shank (d), said tongue or shank being connected to a bar (e) which is fitted and works on a pin (f). This bar (e) has an arm (g) attached to it, against which the teeth or projections (b) on the 45 wheel B, act. To the periphery of the wheel B, there is attached a cord D, which passes through the side of the case A, and has a hook E, attached. To the shank (d) a spring (h) is connected.

50 A¹, represents a bell, which is attached to one side of the case.

The implement or device is placed in the fob, or in the vest pocket, and has a chain attached to the hook E, the device being 55 worn similar to a watch. A pick pocket in pulling the chain to extract the supposed

watch from the pocket, will turn the wheel B, and the teeth or projections (b) on the said wheel will actuate or draw back the hammer C, and the bell will be sounded, the 60 spring (h) throwing the hammer against the bell, and the alarm will consequently be given.

The above device may be worn by police officers in disguise, in order to arrest pick 65 pockets, and as the parts of the device are extremely simple, and may be made quite portable, it may be attached to pocketbooks, watches, etc., and worn without inconvenience by any person, so that a watch or 70 pocket book could not be extracted from the pocket without notice or warning being given the wearer. In fact it may be applied in various ways advantageously, to doors, drawers, or tills, etc.

75 In this arrangement it will be observed that the entire detector, or instrument proper, is suspended by the cord (D) from or through the spring barrel or wheel (B) in independent relationship as it were to 80 the case (A) in such manner that while, on pulling the cord (D) to extract the supposed watch, a sufficient resistance is offered by the action of the spring barrel (B) to induce a continuance of the pull till the 85 alarm is frequently sounded under the impression, by the drawing out of the cord and resistance felt by the winding of the spring on the barrel, that the instrument is being extracted; the instrument is in reality 90 not being disturbed from its place of deposit or rest, the spring (c) only being of the requisite strength to draw in the cord when free and in no wise being used to turn the barrel (B) to sound the alarm but, in 95 addition to the effect above described of producing an illusive resistance, serving to draw in the cord and restore immediately the instrument to its primitive or original condition, after one pull has been made, to 100 meet another pull should the alarm on the previous attempt not have been heard or for certain reasons not have been noticed to induce a repetition of the attempt more favorable to conviction.

105 I do not claim as new in alarm detectors, starting or operating the alarm by pulling or drawing on a cord or its equivalent connected therewith; nor yet as new in such devices, of itself, the mechanism, here employed, of a spring barrel provided with teeth and in its rotation operating the spring

hammer of a bell to give a repeated alarm. But

What I do claim, and desire to secure by Letters Patent, is:

- 5 Suspending the alarm detector or instrument proper, including the case (A) and its working parts, by the cord or chain (D) from or through the spring barrel (B), for alternate operation of the cord and bell

hammer by said barrel in relation to the case, and for the purposes specified.

In testimony whereof, I have hereunto subscribed my name.

SOLOMON W. RUGGLES.

Witnesses:

JAMES W. LEVERETT,
W. J. MERRIAM.
